ICE CUBE CHIPPER

Lucien I. Yeomans, Chicago, Ill., assignor to
 Lucien I. Yeomans, Incorporated, Chicago, Ill.,
 a corporation of Illinois

Application February 1, 1934, Serial No. 709,264

6 Claims. (Cl. 83—62)

The invention relates generally to ice chippers and more particularly to a device for breaking into small pieces ice cubes such as are formed in ordinary electric refrigerators.

5 The general object of the invention is to provide a device of this character which is easy to operate, which effectually reduces the cube of ice to small chips, and which is simple and inexpensive to manufacture.

10 Another object is to provide a manually operable device of this character which by a single movement will reduce the cube to small chips.

A further object is to provide an ice cube chipper having a plurality of picks which are so 15 mounted as to be able to follow the lines of cleavage of ice to prevent undue pressure on the picks and wedging of ice therebetween, and also to facilitate the withdrawal of the picks from the ice.

Still another object is to provide a device of 20 this character which confines the ice while it is being disintegrated to prevent the chips from being scattered about.

Other objects and advantages will become apparent from the following specification taken in 25 connection with the accompanying drawings, in which:

Figure 1 is a side elevation, partially in section, of a device embodying the features of the invention.

30 Fig. 2 is a sectional view taken on the line 2—2 of Fig. 1.

Fig. 3 is an enlarged fragment of a vertical section.

Fig. 4 is a perspective view of a modified form 35 of the device.

Fig. 5 is a sectional view taken on the line 5—5 of Fig. 4.

Fig. 6 is a perspective view of another modified form of the device.

40 Fig. 7 is a vertical section of the form shown in Fig. 6.

In carrying out my invention I provide a hand-operated implement comprising briefly a housing providing a chamber for the cube of ice, and a

45 reciprocating head within the housing carrying a plurality of chipping elements or picks adapted to be driven into the ice by a plunger slidably mounted within the housing and extending externally thereof for convenient operation. Within

50 in the housing is an apertured plate serving to guide the picks when they are first brought into contact with the ice, to limit the sliding movement of the plunger, and to strip the chips of ice from between the picks.

55 In the preferred form of the device, shown in Figs. 1, 2 and 3, the housing, indicated at 10, comprises a strip of sheet metal bent to form a rectangular chamber to receive the ice cube. The ends of the strip are brought into abutment as at 11, and the strip is rigidly held in such form

at its top by a top wall 12 having a downwardly extending flange 13 surrounding the strip. The flange may be secured to the strip as by providing apertures 14 in the strip near the top edge thereof and indenting portions 15 of the flange 5 13 into the apertures 14.

Within the housing 10 is a head, indicated generally at 20, carrying means for disintegrating the ice comprising, in the present instance, a plurality of downwardly extending picks 21 10 adapted to be driven into the ice. The head 20 is so constructed that the picks are loosely supported to permit of a limited lateral movement of the picks as they are driven into the ice so that they may follow different lines of cleavage. To 15 this end, each pick comprises a shank 22 (see Fig. 3) pointed at its lower end and provided with a head 23 at its upper end. The head is made of two spaced plates rigidly secured together as by tangs formed on one of the plates and extending 20 through and bent over the other. The lower plate, indicated at 24, has a plurality of perforations 25, one for each pick, through which the shanks of the picks extend. Each perforation is slightly larger in size than the shank but is less 25 than the size of the head 23. Thus, the picks are held but may move laterally relative to the lower plate 24, to a limited extent.

The upper plate, indicated at 26, is shaped so that, as the picks are forced downwardly, they 30 are permitted to roll slightly against the upper plate. As shown herein, the heads 23 are flat and the top plate is provided with a plurality of rounded bosses 27, one for each pick, bearing 35 against the heads 23. Thus, when the picks are driven into the ice and the ice splits on lines varying slightly from the direction of movement of the picks, the latter are free, because of the rolling or pivotal motion, to follow the lines of cleavage. This prevents undue pressure on the picks 40 and facilitates the removal of the chips of ice from between the picks on withdrawal of the latter.

To operate the device, the head is also provided with a portion extending externally of the housing 45 10, which, in the present instance, comprises a knob 30 projecting from the upper end of a sleeve 31 rigidly secured at its lower end to the upper plate 26 as by means of tangs on the sleeve extending through and bent against the plate. 50 The sleeve is preferably made of a sheet of metal rolled into tubular form. The knob is preferably wood and is secured to the sleeve as by means of nails 32 driven through perforations in the sleeve and into the wood. 55

To guide the head in its movement, it is made substantially the size of the inside of the housing. The top plate 26 is provided with downwardly extending flanges 33 on its four sides and rounded bosses 34 are pressed outwardly on the 60

flanges, preferably two on each side, to bear against the inner face of the housing 10. The head is thus enabled to slide smoothly within the housing without binding. To prevent the head 5 from canting within the housing, the sleeve 31 is slidably guided in the top wall 12 of the housing, an inturned flange 35 being formed around the hole through which the sleeve extends.

The device also includes a means to guide the 10 picks during the first part of their movement downward, which, in the present instance, comprises a plate 40 fixed within and extending across the housing below the head. The plate 40 is provided with a plurality of perforations 41 through 15 which the picks extend and which are slightly larger than the picks. When the head is in its raised position and is separated from the plate, as shown in Fig. 3, the plate is near the pointed ends of the picks. Thus, the difference in size of the 20 perforations in the plate and picks permits only a very slight pivotal movement of the picks and the latter are guided directly against the ice. As the head moves downwardly toward the position 25 where it abuts against the plate, as shown in Fig. 1, the difference in size of the perforations and the picks permits a greater range of pivotal movement of the picks, since the plate is then nearer the pivotal point. Thus, while the plate 40 prevents much pivotal movement of the picks during 30 the first part of the downward movement, it permits a greater movement during the later part of the movement of the head so that the picks are free to follow different lines of cleavage of the ice.

The plate 40 also serves as a stripper. Thus, 35 as the picks are withdrawn upwardly, the plate 40 prevents the chips of ice from being carried with the picks. The plate is preferably so positioned within the housing that it limits the downward movement of the plunger to a point where the 40 pointed ends of picks are a short distance above the lower end of the housing. The picks therefore will not be injured by being driven into a solid supporting base, nor will they injure such supporting base.

To fix the plate 40 within the housing, the ends 45 of the plate are bent downwardly, as at 42, and extend to a point adjacent the lower end of the housing 10. At that point, the ends 42 of the plate are provided with tangs 43 extending through the housing wall and bent against the outer face thereof. The plate thus serves to retain the housing at its lower end in its desired form.

The preferred form of the device shown in Figs. 55 1, 2 and 3 is open at the bottom and is used in connection with a supporting base upon which the ice cube rests when being chipped. In the present instance, the supporting base is shown in the form of a small dish or tray 44 shaped to receive and support the housing 10 when placed over a cube of ice.

In the modified form of the device shown in Figs. 4 and 5, the means for supporting the ice while being chipped is secured to and constitutes 65 a bottom wall for the housing. To this end, a bottom plate 50 is secured to the housing and an opening 51 is provided in the side wall of the housing, through which the ice may be inserted. The bottom plate is preferably movable to a limited extent relative to the side walls of the 70 housing to permit the chips of ice to fall away from the picks on withdrawal of the latter. In the present instance, the ends of the plate 50 are bent upwardly to extend inside of the housing, and each end portion is provided with a pair

of elongated slots 52. Into each slot, a prong 53 is pressed from the end portion 42 of the plate 40. The prongs 53 fit the slots loosely and are shorter than the slots so that the bottom plate is free to drop to a limited extent relative to the 5 housing on lifting the device. Thus, a substantial space is provided below the picks, in which the ice chips may fall. The edge of the bottom plate 50 opposite the opening 51 is also bent upwardly as at 55 to close the gap between the bottom plate and the housing when the bottom plate is in its lower position relative to the housing. 10

To close the opening 51 when the ice is being chipped, the head 20 has a downwardly extending flange 54 positioned adjacent the side wall in 15 which the opening 51 is formed. The flange 54 is of such size that, when the head 20 has moved to its lowest position, the flange 54 closes the opening 51. On withdrawal of the head, the flange moves upwardly so that the ice chips may 20 be removed through the opening 51.

In the form of the device shown in Figs. 6 and 7, the device is provided with a spring to withdraw the picks from the ice. To this end, the operating knob is attached to the head by 25 means of a pair of spaced plates 60, shown in the present instance as integral extensions from the top plate of the head. The spaced plates 60 extend through slots 61 cut in the top wall 12 of the housing and are secured to the knob by 30 means of a member 62 bridging the top edges of the plates 60. The knob, indicated at 63, is preferably made of wood and has a hollow shank 64 resting on the top face of the bridge member 62 and a tubular lining 65 of metal secured to 35 the bridge member 62 by extending therethrough and being flanged against the lower face thereof.

Extending from the top wall 62 is a tubular member 66 the upper end of which enters the lower end of the hollow shank 64 of the knob. 40 Within the tubular member 66 and extending into the knob is a coiled spring 67 bearing at its lower end against the top wall 12 and at its upper end against a headed pin 68 positioned within the knob. The tubular member 66 is 45 preferably secured to the top wall 12 by fitting snugly within a depression 69 formed therein. The spring thus resists downward movement of the head and withdraws the picks when pressure on the knob is released. 50

In this form of the device, the structure permitting the rolling or pivotal motion of the picks relative to the head is attained in a slightly different manner. As shown in Fig. 7, each pick is provided with a spherical head 70, and top plate 55 of the plunger is indented as at 71 to fit over the spherical head. This construction is not necessarily limited to use in this form of the device but may be used in the form shown in Fig. 1 or the form shown in Fig. 4. 60

The relatively fixed parts of the devices shown in Figs. 1 and 4, as mentioned above, are held together by means of bent tangs. Such parts may be held together by spot welding as illustrated in Figs. 6 and 7, either method being suitable for any of the three forms of the device. 65

In using the device shown in Fig. 1, the ice cube is placed on the tray 44. The housing 10 is then placed over the cube with its lower edge resting on the tray. To break up the cube, the 70 knob 20 is given a sharp blow downwardly by the hand. This drives the picks 21 into the cube causing them to break up into small chips. During the first part of the downward movement of the picks, the plate 40 prevents the picks from 75

5 pivoting laterally to any great extent, but as the head 20 approaches the plate 40, the latter is nearer the pivotal point for each pick so that the difference in size between the perforations in the plate 40 and the picks permits a greater range of lateral movement of the picks. The picks are thus enabled to follow the lines of cleavage of the ice, as they are driven downwardly to avoid strain on the picks and prevent binding.

10 The head may be driven downwardly until it strikes the plate 40 which is rigidly secured to the housing. The plate is positioned so that the points of the picks are not allowed to strike the tray 44. The picks are thus saved from becoming unnecessarily dulled and from damaging the tray 44. To remove the ice chips, the knob 30 is lifted upwardly, pulling the picks through the plate 40 and thus depositing the chips in the tray 44. A plurality of cubes may be broken at one 15 time in this manner if they are not too large to be enclosed by the housing.

In the form shown in Fig. 4, the ice cube is placed in the housing 10 through the opening 51. The device is then rested on a table or the like, 20 causing the bottom plate 50 to move to its upper position relative to the housing. A blow or downward push on the knob 30 causes the picks to be driven into the ice, and at the same time, the flange 54 is moved downwardly to close the opening 51. On lifting the knob 30 to withdraw the picks, the housing is lifted permitting the bottom plate 50 to fall to its lower position relative to this housing. This provides space in which the chips may fall and thereby facilitate the withdrawal of the picks.

The form shown in Figs. 6 and 7 is constructed for use with a tray, such as is shown in Fig. 1, or other supporting surface for the ice. On downward movement of the knob 63, the spring is 40 compressed and sufficient energy is thereby stored to return the picks automatically to their withdrawn position.

From the above description, it will be apparent that I have provided a device for breaking cubes 45 of ice into small chips, which is easy to operate, which effectually reduces the cube or cubes of ice to small chips, and which is simple and inexpensive to manufacture. It will also be evident that I have provided a manually-operable device 50 which by a single movement will reduce the ice to small chips, and which confines the chips so that they will not be scattered about. The device includes a plurality of picks which are so mounted as to be able to follow the lines of cleavage of the 55 ice to avoid strain on the picks and prevent binding and also to facilitate the withdrawal of the picks.

I claim as my invention:

1. An ice cube chipper comprising, in combination, a housing providing a chamber to receive and hold a cube of ice, a plurality of laterally spaced picks positioned within the housing and adapted to be projected into the ice, each of said picks comprising a shank having a head at one end, and means for loosely supporting said picks to permit them to follow the lines of cleavage of the ice comprising a pair of spaced plates rigidly secured together, one of said plates being perforated with the picks extending loosely through the perforations, the other of said plates having

a plurality of rounded bosses bearing against the heads of said picks to permit a rolling motion therebetween, and a knob for moving said picks rigidly secured to one of said plates and extending externally of the housing. 5

2. An ice cube chipper comprising, in combination, a housing providing a chamber to receive and hold a cube of ice, a plurality of laterally spaced picks positioned within the housing and adapted to be projected into the ice, each of said picks comprising a shank having a head at one end, and means for loosely supporting said picks to permit them to follow the lines of cleavage of the ice comprising a pair of spaced plates rigidly secured together, one of said plates bearing 10 against the heads of said picks, said heads and said plate being relatively formed to permit a rolling motion of one on the other, the other of said plates having perforations through which said picks extend and said perforations being 15 slightly larger than the shanks of said pins whereby limited lateral movement of the picks is permitted, and means for moving said first-mentioned means.

3. An ice cube chipper comprising, in combination, a housing providing a chamber for an ice cube and having an opening in one side wall through which the ice cube may be inserted, a head slidably mounted in said housing, a plurality of picks movable with said head and adapted 20 to be driven into the ice, and a closure member 25 slidable with said head and movable into a position closing said opening.

4. An ice cube chipper comprising, in combination, a housing providing a chamber for an ice cube and having an opening in one side wall through which the ice cube may be inserted, a head slidably mounted in said housing, a plurality of picks movable with said head and adapted to be driven into the ice, said head having a flange extending 30 downwardly within and alongside said side wall and arranged to close said opening as the head is moved toward the ice. 35

5. An ice cube chipper comprising, in combination, a housing providing a chamber for the ice, 45 a head slidably mounted in said housing, a plurality of picks carried by said head and adapted to be driven into the ice, the end wall of said housing having a pair of spaced slots, a pair of plates rigid with said head and extending through 50 said slots, a knob fixed to the outer ends of said plates for operating said head, said knob being hollow, a tubular member fixed to the outer face of said end wall and extending into the knob, and a spring mounted within said tubular member 55 and said knob and bearing at one end against said end wall and at the other end against said knob to resist movement of the knob and to withdraw the picks from the ice.

6. A disintegrating element for an ice cube 60 chipper comprising, in combination, a perforated plate, a plurality of headed picks having their shanks extending through the perforations in said plate, a second plate rigidly attached to the perforated plate and spaced sufficiently therefrom to allow a limited hinged movement of the heads of said picks, and bosses in said second plate adapted to cooperate with the heads of said picks. 65
